KNOCKDOWN CABINET-TYPE DISPLAY
TABLE

James B. Kelly, Jr., Pittsburgh, Pa., assignor to
Flannery and Associates, Inc., Pittsburgh, Pa.,
a corporation of Pennsylvania

Application March 30, 1948, Serial No. 18,050

5 Claims. (Cl. 312—257)

1

This invention relates to knockdown tables and, in particular, to knockdown cabinet-type tables for displaying merchandise.

It is among the objects of the invention to provide a table which can be quickly and easily knocked down and assembled, which, when knocked down, can be stored or transported in a minimum of space, and which, when assembled is unusually rigid and sturdy and appears as an attractive, integral structure.

The preferred embodiment of the invention is illustrated in the accompanying drawings, of which Fig. 1 is a perspective view of an assembled table minus its doors and interior shelf; Fig. 2 a perspective exploded upside-down view illustrating principally the mode of assembly; Figs. 3, 4 and 5 sections along lines III—III, IV—IV, and V—V of Fig. 1; Fig. 6 a vertical section through the table bottom; Figs. 7 and 8 views of the table's right and left-hand doors; and Fig. 9 a partially broken away view of the table shelf.

Referring to the drawings, the table is made up of a top 1, bottom, or base 2, end panels 3 and 4, rear panel 5, door-frame 6, doors 7 and 8 (Figs. 7 and 8) and shelf 9 (Fig. 9), all of these parts, preferably, being fabricated from light, sheet metal. The marginal edges of top 1 are boxed and, recessed between them is a flat article-supporting plate 12. The boxed edges are formed of a flange which is extended upwardly from plate 12, then outwardly of the table center, downwardly and back inwardly toward the table center, the last projection providing around the table an inwardly extending horizontal flange 14 (Fig. 2). On the under surface of flange 14 there are formed, or secured, corner lugs 16 and central lugs 20, all of which have a later-described function in holding the table together. Also, provided centrally on the underside of the top is a strengthening rib 17. Preferably, all corners of the top, as well as the base and end panels are rounded so as to present a pleasing, finished appearance to the assembled table.

Base 2 is somewhat similar in shape to the table top, except that its flat article-supporting plate 18 is elevated from the floor by an integral platform 19. Thus, from surface 18, the marginal edges are bent upwardly, outwardly, downwardly and inwardly to meet platform 19. The outward bend forms a ledge 21, upon which, as will be explained, other table members rest when assembled. At each corner of surface 18 is provided a locking member receiving opening 22, also to be described.

End panels 3 and 4 play an important part in

2

holding the assembled table members sturdily together and, to do this, their marginal edges have certain configurations which fit into or receive variously shaped elements of other members. However, it should be understood that the invention is not limited to the exact shapes to be described, and that other functionally similar shapes may be substituted.

For appearance, as well as for the purpose of providing interconnecting flanges, the end panels have front and rear side marginal portions 23 and 24 bent inwardly, it being seen that, with such a bend, the end panels provide attractively rounded vertical table corners. Front marginal portions 23 then are bent again at right angles inwardly to provide flanges 26 in which are cut out key-hole slots 27, for purposes later explained. At the bottoms of end panel portions 23 and 24 are formed, or welded, spacing elements 28 (Figs. 2 and 3) which project downwardly and then curve inwardly, the inward flange of these elements being provided with openings 29, which align with openings 22 in the table base corners to receive locking members to be described.

The free edges of rear side-marginal portions 24 are bent into channels 32 (Fig. 3) which face outwardly with respect to the table center, the flanges of these channels, as seen in Fig. 3, being designated channel bottom 33 and side flange 34.

At the top end of each channel 32 is provided an outwardly extending horizontal piece 36 (Figs. 2 and 4) which has an inwardly extending slot 37 adapted to receive previously described corner lugs 16 formed on the underside of the table top. Also, spaced approximately centrally on the inside surface of channels 32 are welded, or bolted, shelf-receiving hooks 38.

The top and bottom marginal edges of the end panels are formed into inwardly extending horizontal flanges 39 and 41, these flanges being cut off short at their ends to allow space for the side pieces 36. Flanges 39 at the tops of the end panels have their free ends turned upwardly back upon themselves to form looped back flanges 42. When assembled, flanges 42 fit around horizontal flange 14 at the ends of the table top and prevent lateral spreading of the end panels.

Rear panel 5, also is specially formed to add to the appearance and rigidity of the table structure. Its top and bottom horizontal edges are bent inwardly into horizontal flanges 43 and 44, top flange 43 being provided centrally with an opening (not shown) into which fits one of the previously-mentioned central lugs 20 located on the under side of the table top. The purpose of

in-turned bottom flange 44 is to rest on ledge 21 of the table base and also to avoid sharp meeting corners.

The vertical side edges of rear panel 5 are specially formed to interconnect with the end panels' channels 32 and, generally, are formed into inwardly facing loops 45 (Fig. 3) which fit around side flange 34 of channels 32. Each of the loops is formed by bending the side edge forwardly toward the table front, outwardly from the table center and then bending the free end back upon itself into the loop. The forwardly projecting portions are bent at right angles to the plane of the rear panel, as are channel bottoms 33 of channels 32, and loops 45 are in the vertical plane of the side flanges 34 of channels 32. The interconnection is shown in Fig. 3, but will be further explained.

The door frame 6 of the table fits between and is detachably secured to flanges 26 of the end panel's inwardly turned side marginal portions. The frame is rectangular in shape and is constructed of inwardly facing channel members. The outside surfaces of the frame end members each bear headed lugs 47, which lock into previously-mentioned key-hole slots 27 of flanges 26.

Doors 7 and 8, the construction of which is clearly shown in Figs. 7 and 8, fit into the top and bottom channels of the frame and slide side-wise therein in the obvious manner. The channels of the door frame are sufficiently wide so that the left and righthand doors can slide by each other.

It is also desirable to provide one or more shelves 9, both for supporting merchandise and rendering the table more rigid. The shelf is supported on hooks 38 of end panels 3 and 4 and its construction is shown in Fig. 9.

Fig. 2 is primarily for the purpose of illustrating assembly of the various parts. The first step is to place table top 1 with its face downwardly on a floor and fit end panels 3 and 4 to it. In so doing, each of these panels is placed on horizontal flange 14 of the top in such a position that slots 37 of end panel pieces 36 are inward of the top's corner lugs 16. The flat of the hand then may be used to gently pound each end panel outwardly, making sure that the slots catch the lugs and, also, that looped-back flanges 42 of the end panels fit around the end portions of the table top's inturned flange 14.

When this engagement is made the end panels will stand erect by themselves and rear panel 5 may be connected to them. As has been suggested, this connection is made by telescopically sliding loops 45 at the rear panel side edges around side flange 34 of end panel channels 32. The resulting inter-connection is shown in Fig. 3. It should be noted that the rear panel is so formed and sized that, when this connection is made, the end and rear panels are drawn tightly together so as to assist in excluding moisture or dirt from the table's interior and to improve the neat appearance of the table. The connection of the rear and end panels is centered when center lug 20 of the top fits into the center opening in the rear panel's top horizontal flange.

Door frame 6 now is attached between flanges 26 at the front of the end panels by inserting its headed lugs 47 in keyhole slots 27 of these flanges. This is possible because, until base 2 is secured, end panels 3 and 4 are capable of being spread apart a sufficient amount to permit the placing of frame 6 between their flanges 26.

Base 2 is next to be secured. It is inverted and

laid down upon the end panels so that its openings 22 align with openings 29 in spacers 28 of the end panels. With this alignment the base then is secured to the end panels by means of fastener elements 51 (Fig. 2). Although any fastening means may be employed, it is desirable to use a type which can be inserted and tightened from the under side of the base. Such an element is shown in Fig. 2 and generally consists of a slotted head 52, a shaft 53 and helical prongs 54 secured to the shaft. The openings 22 and 29 for receiving the shaft are oval in shape and the fastener can be inserted only through the length of the oval. The helix of the prongs is such that when the fastener is turned a quarter turn, the base and end panels are drawn tightly together and the fastener locked. This is a well known type of fastener that is readily available.

Up to this point in the assembly, the parts have all been fitted together in an upside-down position. At this point, the table can be turned right side up, in readiness for the fitting of the shelf and doors. The shelf is fitted in through the door frame and caught in the obvious manner on hooks 38.

It is preferable to fit the doors in the following manner. The right-hand door (Fig. 7) is first urged upwardly, with its flanges facing outwardly, into the top channel of the door frame and then dropped into its bottom channel. These channels, of course, must be deep enough to permit this. The left-hand door (Fig. 8) then is inserted in the same manner, except that its flanges face inwardly toward the center of the table. The right-hand door is moved to the rear of the channels and the left-hand door to the front, so that, in sliding back and forth, the right-hand travels behind the left-hand door. With this arrangement, the doors slide easily and smoothly, since each has only a line contact with the smooth face of the other door, and there is little frictional resistance to the sliding.

The completely assembled table then is ready for use. Actually the time required for its assembly or disassembly is much less than it takes to describe it. The resulting structure is unusually rigid and may be roughly handled without losing this sturdiness. Further, its appearance is very neat and attractive due to the fact that all of the inter-connections are hidden in its inside. A great advantage of such tables is that a number may be kept on hand and quickly set up or taken down as suits the need. When taken down, they may be stored in a minimum space until next use. Also, their transporting is greatly facilitated by the knock-down features.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. A knockdown cabinet-type table comprising a pair of end panels, a rear panel, a top, a base, said end panels having their vertical marginal portions bent inwardly to form the vertical table corners, said rear panel having each of its vertical marginal portions bent interiorly toward the table center and then outwardly from the table center and rearwardly back upon itself to form connecting loops, said inwardly bent portions at the back of said end panels each having an ex-

tension flange bent interiorly toward the table center and then outwardly toward its adjacent table corner, said rear panels connecting loops telescopically engaging said outwardly turned flanges of said end panels, and said telescopic engagement pulling said interiorly bent flanges of both the end panels and the rear panels into tight engagement, each of said end panels also having its upper marginal portions bent horizontally inwardly then upwardly back upon itself 10 into looped flanges which terminate short of the table corners, said table top having its marginal edges bent upwardly, outwardly, and downwardly and terminating in an inwardly extending horizontal flange disposed below the plane of the table top surface, each of said end panels looped flanges fitting around the portion of said table top horizontal flange at the ends of the table and restraining lateral spreading of the end panels, a downwardly extending lug carried near each 20 corner portion of said table top horizontal flange, and horizontal slotted members carried by said end panels between the ends of their looped flanges and their inwardly bent marginal portions, the slots of said members receiving said lugs, and said end panels resting on and being detachably secured to said table base.

2. A knockdown cabinet-type table comprising a pair of end panels, a rear panel, a top, a base, a door frame and doors, said end panels having their vertical marginal portions bent inwardly to form the vertical table corners, said rear panel having each of its vertical marginal portions bent interiorly toward the table center and then outwardly from the table center and rearwardly back upon itself to form connecting loops, said inwardly bent portions at the back of said end panels each having an extension flange bent interiorly toward the table center and then outwardly toward its adjacent table corner, said rear panels connecting loops telescopically engaging said outwardly turned flanges of both the end panels and the rear panels into tight engagement, each of said end panels also having its upper marginal portions bent horizontally inwardly then upwardly back upon itself into looped flanges which terminate short of the table corners, said table top having its marginal edges bent upwardly, outwardly, and downwardly and terminating in an inwardly extending horizontal flange disposed below the plane of the table top surface, each of said end panels looped flanges fitting around the portion of said table top horizontal flange at the ends of the table and restraining lateral spreading of the end panels, a downwardly extending lug carried near each corner portion of said table top horizontal flange, horizontal slotted members carried by said end panels between the ends of their looped flanges and their inwardly bent marginal portions, the slots of said members receiving said lugs, said end panels resting on and being detachably secured to said table base, said door frame being detachably secured between the inwardly bent front marginal portions of the end panels, and said doors being mounted in the door frame.

3. A knockdown cabinet-type table comprising a pair of end panels, a rear panel, a top, a base, a door frame and doors, said end panels having their vertical marginal portions bent inwardly to form the vertical table corners, said rear panel having each of its vertical marginal portions bent interiorly toward the table center and then out-

wardly from the table center and rearwardly back upon itself to form connecting loops, said inwardly bent portions at the back of said end panels each having an extension flange bent interiorly toward the table center and then outwardly toward its adjacent table corner, said rear panels connecting loops telescopically engaging said outwardly turned flanges of said end panels, and said telescopic engagement pulling said interiorly bent flanges of both the end panels and the rear panels into tight engagement, each of said end panels also having its upper marginal portions bent horizontally inwardly then upwardly back upon itself into looped flanges, said table top having its marginal edges bent upwardly, outwardly, downwardly and terminating in an inwardly extending horizontal flange disposed below the plane of the table top surface, each of said end panels looped flanges fitting around the portion of said table top horizontal flange at the ends of the table and restraining lateral spreading of the end panels, said end panels each having its lower marginal portion bent horizontally inwardly and resting on said table base, said base and said end panel being provided at each table corner with aligned openings, base fastening means inserted in said aligned openings and tightened from the underside of said base, said door frame being detachably secured between the inwardly bent front marginal portions of the end panels, and said doors being mounted in the door frame.

4. A knockdown cabinet-type table comprising a pair of end panels, a rear panel, a top, a base, a door frame and doors, said end panels having their vertical marginal portions bent inwardly to form the vertical table corners, said rear panel having each of its vertical marginal portions bent interiorly toward the table center and then outwardly from the table center and rearwardly back upon itself to form connecting loops, said inwardly bent portions at the back of said end panels each having an extension flange bent interiorly toward the table center and then outwardly toward its adjacent table corner, said rear panels connecting loops telescopically engaging said outwardly turned flanges of said end panels, and said telescopic engagement pulling said interiorly bent flanges of both the end panels and the rear panels into tight engagement, each of said end panels also having its upper marginal portions bent horizontally inwardly then upwardly back upon itself into looped flanges which terminate short of the table corners, said table top having its marginal edges bent upwardly, outwardly, downwardly and terminating in an inwardly extending horizontal flange disposed below the plane of the table top surface, each of said end panels looped flanges fitting around the portion of said table top horizontal flange at the ends of the table and restraining lateral spreading of the end panels, a downwardly extending lug carried near each corner portion of said table top horizontal flange, horizontal slotted members carried by said end panels between the ends of their looped flanges and their inwardly bent marginal portions, the slots of said members receiving said lugs, said end panels each having its lower marginal portion bent horizontally inwardly and resting on said table base, said base and said end panel being provided at each table corner with aligned openings, base fastening means inserted in said aligned openings and tightened from the underside of said base, said door frame being detachably secured between the inwardly bent front marginal portions of the end

7
panels, and said doors being mounted in the door frame.

5. A knockdown cabinet-type table comprising end panels having their vertical marginal portions bent inwardly to form vertical table corners, a rear panel interconnected with said vertical marginal portions at the back of said end panels, the marginal portions of said end and rear panels having telescopically engaged flanges forming said interconnection, a base, interlocking means detachably securing the base to the bottom edges of said end panels, a top having an inwardly extending horizontal flange formed around it, said end panels each having an outwardly facing looped flange formed along its upper horizontal edge, said looped flanges terminating short of said table corners and fitting around said top panel horizontal flanges for restraining lateral movement of the end panels, a downwardly extending lug carried near each 20 corner portion of said top panel horizontal flange, horizontal slotted members carried by said end panels between the ends of their looped flanges and their inwardly bent marginal portions, the slots of said members receiving said lugs for se- 25

curing the interconnections of said top and end panels, said interconnections being made by moving said end panels horizontally outwardly to engage said horizontal flanges of the top panel in the looped flanges of the end panels and to simultaneously engage said downwardly extending lugs and said end panel slotted members.
